UNITED STATES PATENT OFFICE.

HENRY C. KESTEL, OF TOLEDO, OHIO.

CLOSURE DEVICE.

1,169,264.

Specification of Letters Patent. Patented Jan. 25, 1916.

Application filed March 1, 1915. Serial No. 11,138.

To all whom it may concern:

Be it known that I, HENRY C. KESTEL, of Toledo, Lucas county, Ohio, a citizen of the United States of America, have invented 5 new and useful Closure Devices, of which the following is a specification.

This invention relates to yieldable walled members and the forming thereof.

This invention has utility in connection 10 with cup shaped articles or caps, especially for vessel closures, as for bottles in the delivery of milk and milk products.

Referring to the drawings, Figure 1 is a fragmentary view in medial section of an 15 embodiment of the invention in a milk bottle closure; Fig. 2 is a fragmentary view of a blank of the sheet or pulp material; Fig. 3 is a side elevation of the cupped blank; Fig. 4 is a side elevation of the dented cupped blank; Fig. 5 is a medial section of the flanged cupped blank having the dented walls in the cup portion; Fig. 6 is a plan view of the blank of Fig. 5, with the flange re-trimmed, and Fig. 7 is a side elevation of the trimmed flange dented wall cupped blank, with the flange bent against the sinuous or dented wall of the cup of the blank.

In the formation of this article, the sheet of material 1, as paper, may be treated to 20 render it susceptible to being re-formed, as by moistening. The circular blank 2 is cut therefrom. This blank 2 is cupped to form the bottom or stiffening portion 3 and the annular cup wall 4. Intermediate the 25 length of this annular wall 4 dents 5 may be formed in this wall to give the wall a sinuous form in its middle section. The next re-formation may be the outwardly flanging of the free terminus of the wall 4 30 to form the flange 6, trimming this flange 6 to properly form flange 7 and bending this trimmed flange 7 back upon the dented portion of the wall of the cup to form the return bend flange or head 8. To enable the 35 article to better resist attacks in use, it may be waterproofed, as by paraffin coating. The completed cap now has the main section or cup bottom 3 with the annular wall rising therefrom in its medial section of sinuous 40 form. The projections or dents 5 in this sinuous wall are yieldable, or rather elastic, as they are tough and will return to initial position, even when compressed con-

siderably. To stiffen the annular wall still more against deformation than the provision of the portion 3, the bead or flange 8 is formed integral with the other elements of the cap.

In bringing the cap into closure acting position, it may be readily pressed into position over the lip or bead 9 of a vessel or bottle 10, and when so snapped down into holding action, the bottle may be lifted thereby, or may even be turned on its side or wrong side up, and the contents still retained in 65 the vessel. There is another automatic feature in the use of the cap having utility in the handling of liquids or substances undergoing volume change under varying atmospheric conditions. With milk or water 70 cooling, or freezing, the expansion does not rupture this cap, nor force it out of bottle closing position. The diaphragm 3 may be shifted outward a little so there may be relief by slight seepage between the dents 5. 75 There is accordingly no opening of the vessel to permit entrance of foreign matter or any occasion to except to the device in any way as but the most superior sanitary vessel closure. The cap may be easily and securely 80 applied with great rapidity, and in itself, it is substantial and secure against accidental removal, but accessible for positive removal when occasion therefor arises. When the vessel is opened, there is no accumulation of 85 fifth which may work into the vessel in taking off the cap. For single service in dairy use, printing may occur before the initial moistening.

What is claimed and it is desired to secure by Letters Patent is:

A cover for a lipped vessel embodying a disk provided with an annular flange having intermediate its extent away from the disk, an endless series of yieldable inwardly extending projections, said flange having beyond said projections a return bend stiffening portion whereby the projections are firmly held to coat with the vessel lip and yieldably draw the disk theretoward.

In testimony whereof I affix my signature in the presence of two witnesses.

HENRY C. KESTEL.
